FINISHING MACHINE FOR STEREOGRAPHIC PRINTING PLATES

Henry A. Wise Wood, New York, N. Y., assignor to Wood Newspaper Machinery Corporation, New York, N. Y., a corporation of Virginia

Original application July 9, 1926, Serial No. 121,403. Divided and this application September 8, 1931, Serial No. 561,634

7 Claims. (Cl. 29—21)

This is a division of my application for patent Serial No. 121,403, filed July 9, 1926, on a Multiple finishing and casting machine for stereotype printing plates.

5 The principal object of this invention is to provide a construction by which one finishing machine can be used in conjunction with a plurality of casting machines, resulting in the production of all the plates in the same time that 10 has been possible heretofore with two complete casting and finishing machines. The invention relates to improvements in the finishing machine to adapt it for this purpose. The invention also involves other improvements as will 15 appear.

Reference is to be had to the accompanying drawings in which

Fig. 1 is a plan of an arrangement whereby two casting machines cast the plates in vertical 20 position and deliver the plates horizontally to a single swivelled finishing machine or unit in accordance with this invention;

Fig. 2 is a side view of the finishing machine partly in central section;

25 Fig. 3 is an end view of the delivery end of the finishing machine with parts in section, and

Fig. 4 is a plan partly in section showing in greater detail a construction by which the finishing machine is operated, with certain modifications 30 not illustrated in the first three figures.

In a stereotype plant in which a stereotype plate is cast and finished in an apparatus with one casting unit and one finishing unit, the finishing unit is idle practically one-half of the 35 time even if the casting unit is being operated as fast as possible. It is obvious therefore that the finishing unit is not used to its fullest extent because it is capable of handling more plates than the casting machine is capable of 40 furnishing. To obviate this difficulty I provide a single finishing unit capable of taking care of the products of a plurality of casting machines and thus introduce savings in the particulars mentioned above.

45 Referring to Fig. 1 I show a furnace 10 provided with two pumps 11, the details of which need not be described, as any suitable pump can be used. Each one is operated independently of the other by a controlling lever 12. Each 50 one delivers through separate spouts 13 to a casting mold.

In this case I have shown two casting machines of well known construction in which, as shown in Fig. 2, the casting is made in a vertical position in a back 14 and then delivered

in horizontal position on a core 15, both of which are supported by a frame 16. Any ordinary type of casting device may be employed.

Two or more of these casting devices, of this type or any other, are arranged in fixed position with their axes at an acute angle with each other. By that I mean that when the plates are delivered on the core 15 they are delivered toward a common point such as 17 which is in alignment with the axes of the cores 15 when 10 in delivering position.

Now I provide a single finishing machine for taking care of the products of the two casting machines and I operate the casting machines alternately so that the finishing machine can 15 finish one casting and deliver it and then receive the other casting while the first casting machine is being filled with metal and the metal is cooling.

The finishing machine is arranged to swivel 20 on the pivot 17 which preferably is equipped with ball bearings. The finishing machine comprises a base 20 having an arcuate track 21 concentric with and supporting the vertical pivot stud 17. Pivoted on this stud is a frame 22 adapted to swing and provided with two or more radial studs 23, each carrying a supporting roll 24 at the end thereof and resting on the track 21. It will be seen that this frame therefore can swing about the stud 17 and that, as indicated in Fig. 1, it can be brought to register, at each end of the oscillation, with one of the casting boxes on the machine. Each casting box is provided with a latch 25 which engages a stud 26 carried by the finishing machine at the end 35 so that the finishing machine is held in alignment with the casting device for receiving the casting therefrom. The spring yields readily at the start of the reverse motion.

I have not shown any means for delivering 40 the casting as this can be done by the ordinary hand methods or automatically as may be desired, or in the case of an inclined machine by gravity.

For the purpose of operating the finishing 45 machine I have shown a motor 30, although of course any desired means can be used for delivering the power. This is geared to a shaft 31 which is geared down in a well known way to the main shaft 33 of the machine. The main 50 shaft, as usual, carries the shaving blade 34 for shaving out the interior of the plate P. From the shaft 33 power is transmitted in a well known way to trimming saws 34a which need not be described in detail.

55

Also from the shaft 33 power is transmitted through a sprocket chain 35 to a shaft 36 and by beveled gears 37 to a vertical shaft 38. This shaft 38 has a crank arm 39 having a pin 40. The base 20 is provided with a longitudinal radial slot 41 into which the pin 40 projects. Now it will be obvious that by the rotation of the shaft 38 the frame 22 will be oscillated back and forth through a certain arc. It has a slight dwell at each casting position.

The shaving machine is also provided with a cooling saddle 45 in line always with the shaving shaft 33.

The gears are of such proportion that when the shaving knife shaft 33 makes one complete rotation, the crank 39 makes a half rotation. Since a cycle consists of a full rotation of the shaving knife shaft it will be obvious that the finishing machine will move from one extreme position to another during each cycle of operation and back again during the next. In this way the time consumed for finishing the plate is used for the automatic movement of the finishing machine from one position to another automatically, without any attention on the part of the operator.

Although I have illustrated and described only one form of the invention I am aware of the fact that modifications can be made therein by any person skilled in the art without departing from the scope of the invention as expressed in the claims. Therefore I do not wish to be limited to the details of construction herein shown and described, but what I claim is:—

35 1. The combination of a frame adapted to swing about a vertical pivot at the center, means on said frame for supporting a stereotype printing plate, means on the frame for shaving the rear surface of the printing plate, rolls at a distance from the pivot for supporting the end 40 of said frame, a track on which the rolls are adapted to run and means for swinging said frame on its pivot to bring it to either end of the track.

45 2. In a plate finishing machine, the combination with a base having a pivot stud arranged vertically, and a horizontal curved track concentric therewith, of a frame arranged to swing on the pivot stud and having rolls arranged on radial studs adapted to run on said track, a stereotype printing plate finishing shaft carried by the frame and arranged in the same vertical plane as the stud and extending radially with respect thereto, and a shaving blade thereon.

3. In a finishing machine, the combination with a base having a pivot stud arranged vertically, and a horizontal curved track concentric therewith, of a frame arranged to swing about the pivot stud and having rolls adapted to run on said track, finishing mechanism carried by said frame, a finishing shaft arranged in vertical alignment with the stud and extending radially with respect thereto and having a shaving blade thereon, an arch carried by the pivoted frame concentric with said shaft, means movable with said frame for driving the shaft, and means connected with said means for swinging the frame about the stud.

4. In a finishing machine, the combination with a pivoted frame, of a radial shaft carried thereby and having a shaving blade thereon, means for rotating the shaft, a second radial shaft carried by the frame at a lower point, means connected with the first shaft for operating the second, and gearing operated by the second shaft and adapted to swing the frame about the stud while the first shaft rotates.

5. In a finishing machine, the combination with a frame adapted to swing about a vertical axis and a fixed base provided with a slot, of a shaving blade shaft carried by the frame in radial position, a shaft on said frame on a vertical axis at a distance from the pivot stud having an arm fixed thereon, means for rotating the second shaft, the arm having a pin projecting into said slot, whereby the rotation of the arm will swing the frame.

6. In a stereotype plate finishing machine, the combination with a base having a radial slot, of a swinging frame pivoted to the base, a shaft on the frame having an arm provided with a pin projecting into said slot, a shaving knife shaft, and means for rotating the two shafts in such relation to each other that the frame 40 will be swung from one extreme to the other while the shaving shaft is completing a revolution.

7. In a stereotype plate finishing machine, the combination with a pivoted frame and a shaving knife shaft mounted thereon, of means on the frame for rotating the shaving knife shaft through two complete revolutions and means on the frame for moving the frame through a complete oscillation forward and back while said 50 shaft is making said two revolutions.

HENRY A. WISE WOOD.
